OSAKA, JAPAN

ROTARY SAMPLE- OR STOCK-CASE STACK

Application filed October 15, 1930. Serial No. 488,836.

The present invention relates to an improved form of a rotary sample- or stock-case stack which substantially comprises a plural-
5 stack which substantially comprises a plural-
ity of cases arranged vertically or horizontal-
ly in an outer framework, each being sus-
pended by a pair of electrically or hand-
driven endless link chains running along two
opposites of said framework, so that the cases
make a positive vertical or horizontal cyclic
10 motion. The object of the invention is to
provide a novel type of case-stack which is
easy to handle and of access and in which the
space required for installation can be fully
utilized.

15 In a stationary case-stack hitherto known,
we must stoop down in handling the lower
cases, while a footstool or ladder is often re-
quired for reaching the upper cases, which re-
sults in a considerable waste of time and la-
20 bor. These defects can be wholly removed
by the present invention, in which any case
can be brought at will to a position most con-
venient for handling.

25 In respect of space economization the pres-
ent invention is decidedly an improvement on
the old stationary type, as it enables us to
utilize fully any retired space, such as the
space near the ceiling, the space under floor or
30 of a recess, etc. This utilization of space can
be effected in a horizontal or vertical direc-
tion, as it is not necessary to leave any space
between two adjacent cases, the cases being
closely juxtaposed and pivotally jointed by
means of levers to the endless link chains.

35 A vertical stock-case stack can be set up di-
rectly against the wall without leaving any
passage between its back and the wall, for
the set of cases in the rear side can be han-
dled from the front. Two sets of vertical
40 case-stack, each provided with two rows of
cases, can be installed back to back. In this
case only two passages instead of three are
required for each front.

45 When a number of horizontal case-stacks
are arranged one upon the other, they may be
handled from the front or rear passage; con-
sequently a further space economization can
be effected, as compared with the vertical
50 type, the number of passages being consider-
ably reduced.

The case-stack according to the present in-
vention can be used with advantage as a book
stack or card-case stack in a library, a show-
case, a stock-case for shoemakers, a stock-case
for spare parts of motor-cars, a stock- or 55
sample-case for apothecaries, for dealers in
provisions, and the like. The stack may also
be applied for posters, show-cards for ad-
vertising, for cyclic exhibition of pictures,
photographs, etc. 60

Practical application of this invention will
now be fully described by way of example in
reference to the accompanying drawings, in
which Fig. 1 is a side elevation of a vertical
case-stack, Fig. 2 a front elevation of same, 65
Fig. 3 an enlarged side elevation of the con-
nection parts of the case and link-chain, Fig.
4 a plan of same. Fig. 5 a modification in
which the link-chains are horizontally dis-
posed, Fig. 6 a front elevation of same, and 70
Fig. 7 an enlarged front elevation of part of
same.

On the top of the outer framework (1) an
electric motor is set up, the shaft of which
extends horizontally in both directions be-
yond the framework and has at its both ends
a pair of chain-wheels (4) keyed thereto. 75
Another pair of chain-wheels (5) (6) are
mounted on the frames. The endless chains
(7) (8) engage the chain-wheels (4) (5) and 80
(4) (6) respectively. The shaft (10) of the
chain-wheel (6) is disposed a little lower
than the shaft (9) of the chain-wheel (5) and
is supported at its other end by a bearing
(11) secured to the frame on the opposite 85
side. The sprocket-wheels (12) (13) are keyed
to the shafts of the chain-wheels (5) (6) re-
spectively. Just below the sprocket wheels
(12) (13) another pair of sprocket-wheels
(16) (17) are supported by the frame, the 90
sprocket-wheel (17) being positioned a little
lower than the sprocket-wheel (16), so that
the interval of elevation between the sprock-
et-wheel (12) and (13) is made equal to that
between the sprocket wheel (16) and (17). 95
The endless link-chains (14) (15) equal in
length engage the sprocket-wheels (12) (16)
and (13) (17) respectively.

Two pairs of parallel guide rails (18) (19)
are laid on both sides of the frame work, so 100

that said endless link chains pass through the space between the guide rail (18) and (19) as clearly shown in Figs. 1, 3 and 4.

To the link at regular intervals of said 5 endless chain a supporting plate (20) is secured, to which a supporting bracket or lever-arm (21) is jointed. The other end of said lever-arm (21) is jointed to the corresponding end of the adjacent supporting bracket 10 or lever-arm (23) by bolt and nut (24), the bolt carrying the frame (26) of the case (25).

It will be noted that the levers (21) (23) carried by the chain 14, for example, are connected to the carrying frame 26 adjacent 15 its upper portion at one end thereof, while the levers (21) (23) carried by the chain 15 are connected to the carrying frame adjacent its lower portion at the opposite end thereof, and that the intervals of elevation 20 between the points of connection of the levers (21) (23) at the respective ends of the carrying frame 26 are substantially equal to the interval of elevation between the axial lines of rotation of the shafts 9 and 10 and 25 the shafts supporting the sprocket wheels 16 and 17.

By such an arrangement, and by reason of the pivotal connections between the levers (21) (23) at their points of connection with 30 the carrying frame and the endless chains, it will be observed that the points of connection of the levers (21) (23) with the carrying frame 26 will maintain their relative positions in a vertical plane extending lengthwise 35 of the carrying frame, and provide a support, at spaced intervals of elevation, to prevent tilting or swinging of the carrying frame and case, which might otherwise result from a one sided or top heavy load contained in the 40 case.

The case (25) is provided with the outer skeleton frame (26) of any suitable form. The upper and lower cases are supported by 45 the levers as closely as possible.

In a modification shown in Fig. 5-7 the both ends of the guide rails (18') (19') are 50 of arcuate form, the middle part of same which is not wanted, being removed. The roller (27) mounted on the shaft (28) which is secured to one end of the lever (21') fixed 55 to the link chain, glides on said guide rails. In this modification the case is supported by said shaft (28).

I claim:

1. In a device of the class described, the combination of a frame work, pairs of sprockets mounted on the respective sides of said frame work, the sprockets of one of said pairs being positioned in a different horizontal 60 plane from the sprockets of the other of said pairs, endless link chains trained around the respective pairs of sprockets, carrying cases, and a plurality of levers operatively connected to said chains and cases for supporting the 65 cases on said chains.

2. A rotary sample- or stock-case stack according to claim 1 characterized by the feature that the endless link-chains carrying the cases are maintained in alignment between the sprockets by two parallel guide-rails laid 70 on the frame-work.

3. A rotary sample- or stock-case stack according to claim 1 characterized by supporting plates carried by said chains and by the feature that one end of the levers is jointed to 75 the supporting plate secured to the endless link chain, and the other end to the carrying case.

4. A rotary sample- or stock-case stack according to claim 1 characterized by shafts 80 mounted on said levers and the feature that rollers revolvably mounted on one end of the shaft secured to the lever carried by the endless link-chain are supported by two parallel guide rails horizontally disposed and with 85 both ends in arcuate form.

5. In a device of the class described, the combination of a frame work, a plurality of pairs of sprockets mounted on said frame work, one of said pairs of sprockets being positioned above the other pair, endless link chains of substantially equal length trained around the respective pairs of sprockets, a carrying frame, and supporting brackets carried by the respective chains, the bracket carried by the chain engaging the lower pair 90 of sprockets being pivotally connected to said carrying frame adjacent the lower portion thereof and the bracket carried by the chain engaging the upper pair of sprockets 95 being pivotally connected to said carrying frame adjacent the upper portion thereof.

6. In a device of the class described, the combination of a frame work, a plurality of pairs of sprockets mounted on said frame 100 work at opposite sides thereof respectively, one of said pairs of sprockets being positioned above the other pair, endless link chains of substantially equal length trained around the respective pairs of sprockets, a carrying frame, and supporting brackets carried by the respective chains, the bracket carried by the chain engaging the lower pair 105 of sprockets being pivotally connected to said carrying frame adjacent its lower portion and at one end thereof, and the bracket carried by the chain engaging the upper pair of sprockets being pivotally connected to said carrying frame adjacent its upper portion 110 and at the opposite end thereof.

7. In a device of the class described, the combination of a frame work, a plurality of pairs of sprockets mounted on said frame work, one of said pairs of sprockets being positioned at an interval of elevation above 115 the other pair, endless chains of substantially equal length trained around the respective pairs of sprockets, a carrying frame, and supporting brackets carried by the respective chains, the bracket carried by the 120

125

130

chain engaging the lower pair of sprockets being pivotally connected to said carrying frame at one end thereof and the bracket carried by the chain engaging the upper pair of sprockets being pivotally connected to the opposite end of said carrying frame at an interval of elevation above the pivotal connection of said previously mentioned bracket substantially equal to the interval of elevation between the respective pairs of sprockets.

8. In a device of the class described, the combination of a frame work, a plurality of pairs of sprockets mounted on said frame work at opposite sides thereof, one of said pairs of sprockets being positioned at an interval of elevation above the other pair, endless link chains of substantially equal length trained around the respective pairs of sprockets, a carrying frame, and supporting brackets carried by the respective chains, the bracket carried by the chain engaging the lower pair of sprockets being pivotally connected to said carrying frame adjacent its lower portion at one end thereof and the bracket carried by the chain engaging the upper pair of sprockets being pivotally connected to said carrying frame adjacent its upper portion at the opposite end thereof and at an interval of elevation above the pivotal connection of said previously mentioned bracket substantially equal to the interval of elevation between the respective pairs of sprockets.

35 9. In a device of the class described, the combination of a frame work, a plurality of pairs of sprockets mounted on said frame work at opposite sides thereof, one of said pairs of sprockets being positioned at an interval of elevation above the other pair, endless link chains of substantially equal length trained around the respective pairs of sprockets, a carrying frame, supporting brackets carried by the respective chains, the bracket carried by the chain engaging the lower pair of sprockets being pivotally connected to said carrying frame adjacent its lower portion at one end thereof and the bracket carried by the chain engaging the upper pair of sprockets being pivotally connected to said carrying frame adjacent its upper portion at the opposite end thereof and at an interval of elevation above the pivotal connection of said previously mentioned bracket substantially equal to the interval of elevation between the respective pairs of sprocket wheels, and a plurality of substantially parallel guide rails positioned on said frame work between the sprockets of the respective pairs and operatively related to said link chains for maintaining the links thereof in substantial alignment throughout their travel between said sprockets.

65 10. In a device of the class described, the

combination of a frame work, a plurality of sprockets mounted at opposite sides of said frame work, endless link chains trained around the sprockets at respective sides of the frame work, the sprockets at one side of the frame work around which one of said chains is trained being positioned in different horizontal planes from the sprockets at the other side of said frame work around which the other link chain is trained, carrying cases, and means operatively connected to said chains and cases for supporting the cases on said chains.

11. In a device of the class described, the combination of a frame work, a plurality of sprockets mounted at opposite sides of said frame work, endless link chains of substantially equal length trained around the sprockets at the respective sides of the frame work, the axial lines of the sprockets at one side of the frame work around which one of said chains is trained being positioned in different planes from the axial lines of the sprockets at the other side of said frame work around which the other link chain is trained, carrying cases, and means operatively connected to said chains and cases for supporting the cases on said chains.
